UNITED STATES PATENT OFFICE.

JOHN ARMSTRONG, OF LONDON, ENGLAND.

FURNACE.

SPECIFICATION forming part of Letters Patent No. 722,932, dated March 17, 1903.

Application filed October 6, 1902. Serial No. 126,228. (No model.)

To all whom it may concern:

Be it known that I, JOHN ARMSTRONG, civil engineer, a subject of the King of Great Britain, residing in the city of London, England, (whose full postal address is 46 Lombard street, London, aforesaid,) have invented certain new and useful Improvements in Furnaces, (for which application has been made in Great Britain, No. 4,154, dated February 18, 1902,) of which the following is a specification.

This invention has for its object an improvement upon my former patent, No. 705,312, dated July 22, 1902, whereby it is made applicable for heating reverberatory furnaces for evaporators, retorts, refuse-destructors, and for furnaces for smelting, roasting, baking, heating, melting, and other purposes where complete combustion is required and very high temperatures can be obtained.

In my former patent, No. 705,312, it will be observed that the design of that invention was not for the purpose of complete combustion of the fuel to carbonic acid, but, on the contrary, the formation of carbon monoxid—a reducing-gas—for the purposes mentioned in that patent. In the present invention, however, I have modified the apparatus and made arrangements for the purpose of the complete combustion of the fuel. It will also be shown, together with the last-named object, that the operator can with the present invention have complete control of the heat developed by means of primary and secondary air-blast inlets, steam-jets, &c. Provision is made for the reservation of all the unaltered fuel at the rear of the consumption or oxidizing hearth, thus preventing the raw fuel attaining the surface of that part of the fire where the fuel is properly consumed, whereby smoke is prevented, the object being to have a constantly clear fire always exposed to the furnace-hearth to be heated.

Figures 1 and 2 show longitudinal sections of two slightly-different forms of my apparatus as applied to a reverberatory furnace for puddling iron, melting steel, smelting or refining copper, or for other like purpose.

It will be seen that *x x* represent the hearth of an ordinary puddling-furnace.

y is the lower bridge.

aa represent the grate, which can be of any

ordinary type, but is here shown constructed of a plate perforated with numerous conical holes all over its surface.

5:

b is a frame set into the brickwork for holding the above grate, and *c* represents plates connected with the frame *b* and dipping down beneath the surface of the water *w w* in Fig. 2, thereby forming an air-chamber *d d*.

6:

A door is provided at *n*, which can be moved on hinges against the dead-plate *o*. This door is used for the purpose of pushing forward the fire and removing clinkers.

The space *pp* is the reservoir containing the fuel. This may be surmounted by a cup-and-cone apparatus or a shot-flask apparatus (not shown) for the purpose of letting down the fuel without allowing the smoke or gas to escape. This chamber is shown of solid brick-

7

work. There is a front upper pendent bridge provided at *s*, which keeps the fuel back until that which is on the grate is consumed. There are doors *m* provided, preferably at both sides of the furnace, although one may be used for the purpose of spreading the fuel or removing clinkers. The line of the fuel is shown at *g g*, which descends upon the grate at an angle. A primary blast of air is supplied from a blower by the pipe *e*, which

8

air passing into the fire from the air-chamber *d d* consumes the fuel immediately upon the grate to carbonic acid. The smoke and gas produced by the heat radiating into the chamber *pp* and finding no outlet at the top are made to traverse the incandescent coke at *g*, forming carbon-monoxid gas and hydrocarbons. These would pass right through the furnace unconsumed, because the atmospheric air blown in through the grate having to traverse so much incandescent coke becomes de-

9

oxidized, and thereby incapable of consuming these gases. To prevent this, a heating-chamber is constructed, filled loosely with bricks, over the furnace-roof at *l*. A secondary air-blast is made to traverse this chamber *l*, whereby the air is heated and descends through the apertures *t*, whereby all these gases are completely consumed and the action of the heated air, together with the rear upper pendent bridge *r*, Fig. 1, directs the flame down upon the hearth.

9:

z is an air-blast pipe connecting the primary air-blast with the heating-chamber. In

Fig. 1 this air-blast pipe z is shown connected directly with the primary air-blast pipe; but in Fig. 2 it is shown connected with the primary air-blast chamber.

Where there is no convenient source of power for blowing purposes, a steam-jet may be used, as at ff' , and such steam may be beneficial, especially when working with fuel of a very inferior nature. The action of the steam in such case is twofold. In the first place, it is used to soften and break up the clinker, and, in the second place, passing in with the air through the incandescent fuel, it is decomposed and split up into carbon mon-
oxid and hydrogen gases. These are consumed, as has been already stated, by means of the secondary air-inlets at t . The steam, however, supplies no additional heat and is often deleterious. When, therefore, the blast is effected by steam-jets, I may bring the entire blast down through or in close contact with water by means of a downwardly inclined blast-pipe e' , as shown in Fig. 2, whereby most of the steam is condensed, and so does not enter the furnace with the air.

Fig. 1 shows the air-chamber constructed as a box for collecting any dust that may fall through the apertures in the grate a . Means are provided for removing this dust by the valve S . In Fig. 2 the dust falls into the water and can from time to time be raked out through any side aperture. (Not shown.)

Apertures h' are provided above the door n for the purpose of inserting spears for holding up the fuel while the grate a is dropped. A valve is provided in Fig. 1 at S for the purpose of clearing away any dust.

The air-blast, whether by means of an air-blower or by means of a steam-jet or compressed-air jet, whether as primary or secondary, is provided with the usual cocks and valves (not shown) for regulation.

For reverberatory-furnace purposes it will be evident that the forcing in of the air or air and steam is for the purpose of completely consuming the fuel without the aid of a draft by means of a chimney-stack. By this means the furnace can be easily made to have a plus-pressure atmosphere in its interior, whereby the entrance of the cold atmosphere or oxidizing drafts so destructive in metallurgical and other operations is entirely avoided. Although these applications have been shown for reverberatory and other furnace work, they can be made applicable to ovens for baking bread or biscuits, for baking or firing pottery or bricks in kilns, where they are made to take the place of the ordinary fire-grate. Any number of these grates can be placed around a furnace or kiln.

This furnace may be used as a destructor by supplying the refuse to be destroyed, either with or without fuel, into the compartment pp .

As this furnace burns the fuel as well as all the gas and smoke produced to carbonic acid, the full theoretical amount of calories may be obtained by it. It will therefore be

more economical in use practically than gas-furnaces generally or ordinarily-fired furnaces, because all the initial heat of the complete oxidation of the fuel to CO_2 is thrown direct and immediately into the furnace-hearth x without loss and the highest temperature obtained. The grate a being solid, only being perforated with small holes, no unconsumed fuel is allowed to drop through, and this grate a being placed in immediate contiguity to the furnace-hearth x , while the raw fuel is kept behind the bridge s over the dead-plate o , the surface of the incandescent fuel over the grate a is always bright and no cold fuel comes upon its surface. Consequently the full heat is unrestricted. This is very important in certain metallurgical operations and in the heating or firing of retorts where it is used. By the regulation of the valves of the primary and secondary air a neutral reducing or oxidizing atmosphere can be maintained at will.

This invention differs from all that has gone before in these respects: that the supply of oxygen can be exactly regulated, the whole of the oxygen of the air passing through the grate being under pressure passed in in regulated quantities and largely converted into carbonic oxid, and as the amount of air passing through the air-inlets t can be regulated exactly all the carbonic oxid can be converted without waste into carbonic acid, while at the same time as the coal is delivered at the front of the grate and by gravity settles to the back of the grate after it has been to a considerable extent coked there is always a brilliant-red surface exposed to the furnace-hearth, while by using the device set forth in Fig. 2 the entire blast can be effected by steam-jet without any sensible amount of steam escaping into the furnace, and there being always a plus pressure in the furnace leakage inward is impossible, and thus even when working doors are opened the action of the furnace remains constant.

I declare that what I claim is—

1. A furnace comprising a grate-frame having a grate, a bridge, a dead-plate located in front of the grate-frame, a reservoir through which the fuel extends over the dead-plate and the grate to the bridge, an air-chamber located beneath the grate, a primary air-blast pipe extending into the air-chamber, an upper heating-chamber having secondary air-blast inlets located in rear of the fuel, and an air-blast pipe connecting the primary air-blast with the heating-chamber.

2. A furnace comprising a grate, an air-chamber beneath the grate, a water-chamber into which the air-chamber dips, and an air-blast pipe extending into the air-chamber and downwardly into the water-chamber and a steam-pipe having a jet-pipe extending into the air-blast pipe.

3. In a furnace supplied with blast by means of a steam-jet; the combination of the grate a ; depending walls c, c , forming an air-

chamber *d*, beneath the grate; water-chamber *w*; steam-pipe *f*, having a jet-pipe *f'*; and downwardly-inclined blast-pipe *e'* adapted to deliver the blast below the surface of water in chamber *w*; whereby steam is condensed and air delivered under pressure to the furnace, substantially as described.

In witness whereof I have hereunto signed my name, this 24th day of September, 1902, in the presence of two subscribing witnesses.

JOHN ARMSTRONG.
